UNITED STATES PATENT OFFICE.

HENRY A. GEHRET, OF READING, PENNSYLVANIA, ASSIGNOR OF ONE-HALF
TO WILLIAM F. MARKS, OF SAME PLACE.

CAR-DOOR FASTENER.

SPECIFICATION forming part of Letters Patent No. 350,977, dated October 19, 1886.

Application filed January 18, 1886. Serial No. 188,937. (No model.)

To all whom it may concern:

Be it known that I, HENRY A. GEHRET, a citizen of the United States, residing at the city of Reading, county of Berks, State of Pennsylvania, have invented a new and useful Improvement in Car-Door Fasteners, of which the following is a specification.

This invention pertains more particularly to a fastener for a sliding door of a freight-car or its equivalent.

The object of the invention is to furnish a lock that will be inexpensive and that will lock the door in a closed or fully-opened position or at any point desired intermediate thereto.

The great difficulty in freight transportation at the present time is to secure a positive lock to the doors of the cars. In nearly every case after the door is closed and the lock secured the precaution is taken to insure closure, of nailing strips of wood against the car with the edge of the strip in close contact with the edge of the door, the result of which is, that in a short time the car-sheathing next to the door is so completely cut up with nail-holes that it will no longer hold the blocks and must be renewed.

My improvement in fasteners positively secures the door in close contact with the closing-strip, and when so closed it cannot be disturbed, but will retain the door immovably in place.

In the drawings herewith, forming a part of this specification, and in which similar letters of reference indicate similar parts, Figure 1 represents in side elevation a portion of a car with the sliding door closed, showing the improved fastener attached thereto. Fig. 2 represents the fastener detached from the car. Fig. 3 represents in plan and longitudinal section the keeper-plate used in connection with the improved fastener, in all of which—

A represents the body of the car; A', the closing-strip; A'', the sill; B, the guide-rail; C, the door-hangers; C', the anti-friction rollers; D, the door, and E the usual door-stop.

The fastener is composed of a body, F, with bearing portions F', and integral with the body a hasp-plate, G, with the usual staple-slot, G', and at right angles to the same, upon the outer end of one of the bearings F', a locking-arm,

H, of a length sufficient to reach from the outer face of the door, within the thickness of the car-sheathing. The arm may be thickened at H' to form a hub, and, if thought preferable, 55 may be fitted to the end F', and suitably secured thereto. I prefer, however, to have the body F, hasp G, and arm H cast or formed of suitable metal as one integral piece.

The keeper-plate K is made of suitable 6c length to admit the sweep of the arm H in its slot K', which is formed with parallel sides and a concave base, thus preventing any accumulation of dirt or retention of water therein. The pieces K are secured to the car-body at 65 suitable points, indicated by the position it is desired the door shall assume during transit.

I usually place the fastener with the arm H in contact with the free edge of the door, as shown in Fig. 1, and the keeper-plate K immediately beneath the door-face in line with the arm H. This arrangement brings the screws K² 70 partially beneath the door, and adds to the security of the lock. I also place a keeper-plate near the stop E, and if the goods carried in 75 the car are of such nature as to require a free supply of air I place one or more of the keeper-plates intermediate to the outer ones. This enables me to lock the door close against the closing-strip A', or to lock it with an opening 80 between the strip and door of any width determined by the position of the keeper-plates upon the side of the cars.

The fasteners may be secured to the doors by staples I, of the usual form, or the bearings F' 85 may be rested in special boxes adapted thereto. A staple, J, is secured to the door, so that when the hasp G is turned up (which action turns the arm H down into the keeper) the slot G', formed in said hasp, will engage the staple and permit the usual car-seal to be applied.

The keeper-plate K may be made with any desired number of parallel slots for connection with the closed door, and it may be placed entirely behind the door, in which case the arm H would be made to play in a slot cut through the door. I prefer the single-slot form and the outside connection, as shown.

I am aware that Patent No. 334,840, January 26, 1886, was issued to A. B. Barnard for a 100 car-door fastener in principle somewhat like my invention; but in this case the device is

secured to the edge of the door with the operative locking-arm hid beneath the same. My device, on the contrary, is applied to the face of the door with all of its parts exposed for inspection. This arrangement permits of ready adjustment of parts to meet changes incidental to straining and distortions of cars. Outside of the functional duty of locking the door, the devices are dissimilar in application and construction.

Having described my fastener, and shown its use and advantages, I desire to secure by Letters Patent the following claims thereon:

1. In a car-door fastener, the combination, with a locking device composed of a body having a locking-arm at right angles thereto, and a slotted hasp formed integral therewith, of a

series of keeper-plates secured to the face of the car, and adapted to be engaged by the arm of said locking device, substantially as 20 and for the purpose set forth.

2. In a car-door fastener, a keeper-plate, K, having one or more parallel sides, and concave-backed slots suitably secured to the face of the car-body, in combination with a staple 25 and a fastener secured to the outer surface of the door, and composed of the body F, having arm H and slotted hasp G, substantially as shown, described, and for the purpose set forth.

HENRY A. GEHRET.
